UNITED STATES PATENT OFFICE.

ADOLPH SIMON, OF JERSEY CITY, NEW JERSEY.

DESIGN FOR WEATHER-VANES.

Specification forming part of Design No. **7,381**, dated April 14, 1874; application filed March 24, 1874.
[Term of Patent 7 years.]

To all whom it may concern:

Be it known that I, ADOLPH SIMON, of Jersey City, in the county of Hudson and State of New Jersey, have invented a Design for Weather-Vanes, of which the following is a specification:

The nature of my design is fully represented in the accompanying engraving, to which reference is made.

A represents the frame of the vane, which may be of any desirable form; and B, a figure which forms the vane proper. This figure B is made to represent King Gambrinus in a standing position, with his right foot advanced and resting on a barrel or keg, C. The feet and lower portions of the legs of the same are

clad with riding-boots *a* and spurs *b*, and a long robe, *c*, which passes from the shoulders over the back of the figure down to the frame A, is made to fall behind the figure. I prefer to have the entire figure gilt, but I do not consider this an essential element in my design.

I am aware that pictures of King Gambrinus have been made before, but never in position and style as herein shown and described.

What I claim as my invention is—

A design for weather-vanes, substantially as herein shown and described.

ADOLPH SIMON.
